UNITED STATES PATENT OFFICE.

MAXIMILIAN K. GOLDEN, OF SAN FRANCISCO, CALIFORNIA.

ELECTRICAL VIBRATOR.

No. 892,249.

Specification of Letters Patent. Patented June 30, 1908.

Application filed February 19, 1908. Serial No. 416,745.

To all whom it may concern:

Be it known that I, MAXIMILIAN K. GOLDEN, citizen of the United States, residing in the city and county of San Francisco and State of California, have invented new and useful Improvements in Electrical Vibrators, of which the following is a specification.

My invention relates to an electrically actuated vibrating device.

10 It consists in a combination of parts, and in details of construction, which will be more fully explained by reference to the accompanying drawings, in which

15 Figure 1 is a horizontal section or plan view with the cap removed. Fig. 2 is a vertical section of the same.

It is the object of my invention to produce a vibrating device which may be operated by an electrical current, without the use of 20 sparking device, induction current, or make and break mechanism, such as is usually employed for such devices; and it includes a means for greatly increasing the power of the apparatus.

25 It is applicable for the moving of reciprocating parts of any kind which can be so moved, such as the ringing of bells, the actuating of massage or percussion implements, or anything of a like character.

30 As shown in the present structure, A is an inclosing shell which is adapted to contain a plurality of electro-magnets, as 2 and 2^a. One or more of the magnets 2 is mounted upon a yielding or spring arm, or equivalent 35 3, which is here shown fixed at one side, as at 4, within the casing A, so that by means of this movable arm the magnet itself is capable of motion in unison with the movement of the arm.

40 The arm 3 is formed continuously with an arm or bar 3^a which extends across the interior of the case behind the magnets 2, and has its opposite end secured to the interior of the case opposite to the fastening 4, as shown 45 at 4^a. One or more magnets 2^a are mounted upon the fixed arm 3^a substantially parallel with the movable magnets 2. The movable arm 3 carries an armature in line with the core of the electro magnet 2^a. 8 is another 50 armature which is fixed to the bar 3^a, and acts in conjunction with the electro magnet 2. As the electro magnet 2 is mounted upon the vibrating arm 3, it will be seen that as it is alternately energized and deenergized, the 55 armature being stationary, the magnet 2 will be alternately attracted to, and released

from, the armature 8. At the same time, the circuit being also completed through the electro magnet 2^a, which is stationary, it will attract its armature 8^a, which is carried upon the vibrating arm 3, so that I employ the double power of the magnets 2 and 2^a acting upon the same vibrating arm 3. This greatly increases the power of the apparatus.

It will be seen that the weight of the electro magnet 2 adds a very considerable force to the operation of the vibrating arm, and anything which may be carried thereby.

In order to regulate and control the amplitude of the vibrations of the arm 3, I have shown a rod or stem 13 which extends through the side of the case, its inner screw-threaded end terminating near the arm 3.

The outer end of the screw 13 may have a milled head, or other device by which it can be turned, without advancing, being prevented by a collar 14 fixed to it inside the case. The inner screw-threaded part is turnable in a polygonal nut 15 which fits loosely in an opening in the arm 3^a. Between this nut 15 and the vibrating arm 3 is a spiral spring 16 which incloses the screw stem, and its ends may contact with the arm and with the nut respectively. By turning the screw, the nut 15 may be advanced to compress the spring and increase its tension and pressure upon the vibrating arm, and by retracting the nut, the tension and pressure is correspondingly reduced.

In order to hold the screw 13 and nut at any desired point, the sides of the collar 14 contact with an elastic arm or spring 17, so that whenever the screw is turned, any portion of a revolution, the flat side of the collar contacting with the spring, will be held and prevented from further turning.

The part to be moved by the movement of the spring 3 may either be in direct line, by means of a rod so disposed with relation to the arm 3 that it will be actuated with direct push by such vibrations, or it may be connected directly with vibrating arm as at 18.

A direct connection is shown by means of an arm having the inner end fixed to the vibrating arm 3, and itself extending through an opening 7 in the side of the case; and this outer end has attached to it any implement or device to which it is desired to impart a vibrating motion. Thus, an implement attached to the end of the direct arm would be moved longitudinally, providing a reciprocating or percussion movement of such

strength as might be desired. If attached, on the other hand, to the end of the arm, 6, it would receive a transverse movement; and the weight of the electro magnet carried upon 5 the movable arm insures a positive movement, by reason of the momentum imparted to it, while the action of the second magnet 2^a in unison with the first, adds great strength to the movement.

10 As illustrated in the present device, the case A may be provided with a handle 10, which is preferably hollow, and serves for the introduction of the cable 9, which is composed of separate insulated wires, which 15 wires are connected with the magnet coils in the usual, or any suitable manner, as shown at 11.

The construction is very advantageous, inasmuch as I am able to dispense with the 20 make and break mechanism, with the necessary induction current and sparking device, which may be thus entirely eliminated.

The apparatus may be employed to ring 25 bells in connection with telephones, and by reason of the considerable power which it has, it can be used in various percussion movements, such as dental hammers, and the like.

Having thus described my invention, what 30 I claim and desire to secure by Letters Patent is—

1. An apparatus for producing vibratory movements, said apparatus consisting of a

vibratory arm fixed at one end, having the free end adapted to carry an implement or 35 tool, a magnet carried by said arm, a stationary armature coacting with the magnet, a second and stationary magnet, and an armature therefor carried by the arm, said magnets coacting when energized. 40

2. In an apparatus for producing vibratory movements, an arm fixed at one end whereby it may vibrate, means for connecting the free portions of the arm with implements or tools to be actuated, an electro 45 magnet fixed to, and movable with, the arm, a stationary armature coacting with said magnet, a second and stationary magnet, and an armature carried by the arm and coacting with said second magnet. 50

3. A device for regulating the amplitude of vibration, said device including a vibrating arm, a screw in the line of vibration and turnable through a movable nut, a spiral spring disposed between the nut and the vibrating arm, and a locking device whereby the screw is retained at any point of adjustment. 55

In testimony whereof I have hereunto set my hand in presence of two subscribing witnesses. 60

MAXIMILIAN K. GOLDEN.
